UNITED STATES PATENT OFFICE.

FRANK J. HELMUTH, OF OAKLAND, CALIFORNIA.

LOCK.

Original application filed March 17, 1926, Serial No. 95,340. Divided and this application filed July 29, 1926. Serial No. 125,660.

The present invention relates to improvement in locks and has particular reference to a door lock. The principal object of the invention is to provide a lock of the character described that is particularly well constructed and difficult to open without the aid of a key made for the same.

The present application is divisional to application Serial No. 95,340, filed March 17, 10 1926.

The preferred form of my invention is illustrated in the accompanying drawing in which—

Figure 1 shows an axial section thru my 15 lock,

Figure 2 a transverse section thru the same,

Figure 3 an end view of the tumbler arrangement as viewed from the rear,

20 Figures 4 and 5 detailed views graphically illustrating the cooperation between the key and the tumbler,

Figure 6 a longitudinal section thru a tubular element cooperating with the tumbler arrangement, and

25 Figure 7 an end view of the latter.

While I have shown only the preferred form of my invention, it should be understood that various changes or modifications 30 may be made within the scope of the claims hereto attached without departing from the spirit of the invention.

In its preferred form, my lock comprises 35 a tumbler arrangement accommodated in the tumbler housing 1 and adapted to be used in connection with the bolt operating mechanism arranged in a rectangular flat case 2, which latter may be inserted into the edge of a door in a manner well known in the art. The housing 1 is adapted for insertion thru a transverse hole and to be threaded into the case after the latter has been inserted as shown at 3 in Figure 1. The front end of the housing is provided 40 with a slight conical flange 4 and receives before insertion, a conical ring 6 adapted to bear on the plate 7 customarily arranged on doors in combination with locks of this character. The housing is firmly held against 45 rotary motion by means of a set screw introduced from the edge of the door thru a hole in the plate 9 and this set screw extends thru a tube 11 disposed on the inside of the housing so that this tube is also held against 50 rotary motion. The tube is provided with

a plurality of longitudinal slots 12 connecting each with a transverse slot 13. A cylinder 14 is revolvable in this tube 11, but is held against endwise motion by means of a flange 16 bearing on the outer end of the 50 tube 11 and seated in a recess 17 in the housing and at the other end by a plate 18 secured to the cylinder by means of screws 19.

The cylinder is formed with a plurality of radial slots 21 adapted to slidably receive 55 registering flat tumblers 22 having pins 23 projecting forwardly therefrom and extending into small holes 24 through which prongs 26 of a key 27 may be inserted. The length of the pins 23 and the prongs 26 is such that 60 when the key 27 is fully inserted, the pins 23 and, with them, the tumblers 22 are pushed backwards sufficiently far to allow 65 outward projections 28 extending from the tumblers into the longitudinal slots 12 to 70 register with the transverse slots 13 and to be pushed therewith by a revolving motion 75 of the key. The latter is formed with a central guiding member 29 adapted for insertion in a perforation 31 in the cylinder for 80 steadying the key. The guide member is preferably notched as shown in 32 to allow a spring 33 in the perforation 31 to catch 85 therein. Springs 34 guided by pins 36 tend to push the tumblers toward the front while 90 a spiral 37 accommodated in a recess 38 within the cylinder 14 tends to return the cylinder to its initial position from a rotary 95 excursion. The rotary motion of the cylinder is limited by a pin 35 extending from the rear edge of the housing and riding in a peripheral recess 40 formed in the plate 18. A retractable dog 41 projects from the plate 18 and has a spring 42 associated therewith tending to force the same outwardly. This dog is used for transferring 100 rotary motion from the cylinder 14 to the bolt operating mechanism, which latter is shown in detail in the co-pending application of which this forms a subdivision and 105 which includes as actuating member a ratchet 43 mounted co-axially with the cylinder and allowing the dog 41 to ride thereon. The ratchet is held against backward 110 motion by a pawl 44 engaging with another ratchet 46 fixed relative to the ratchet 43 so that on the return motion of the cylinder 14, the dog 41 rides over the slanting face 47 of a ratchet tooth to engage with the other steep face thereof for the next turn. The 115

operation of my locking device as far as described in the present application is as follows:

To operate the same, a key is inserted which pushes the tumblers 22 backward over the resistance of the springs 34 until the projecting prongs 28 register with the transverse slots 13 in the tube 11 and allow the cylinder to be turned against the opposition of the spring 37, the turning movement being limited by the pin 35. This turning movement is transferred to the ratchet 43 by the dog 41 and causes the ratchet to advance by the length of one tooth. As the operator releases the key, the cylinder 14 returns to its initial position due to the action of the spring 37 while the dog 41 climbs over the slanting face 47 of the next tooth for engagement with the steep face 48 thereof. The return of the cylinder to its initial position causes the projections 28 to again register with the longitudinal slots in the tube 11 and allows the tumblers to return to their initial position due to the action of the springs 34.

I claim:

1. In a lock of the character described, a stationary element, a member mounted therein with freedom of rotary motion through a limited arc and having yielding means associated therewith urging the latter to an initial position, means normally locking the member in an initial position made to yield to the insertion of a key, and a

spring pressed plunger projecting eccentrically from an end face of the member adapted to ride on a ratchet for advancing the same when the member is turned in one direction and taking a new bite when the member is turned in the opposite direction. 35

2. In a lock of the character described, a stationary element, a member revolvable relative thereto, means normally locking the member to the element yielding to the insertion of a key and a spring pressed plunger 40 projecting eccentrically from an end face of the member adapted to ride on a ratchet for advancing the same when the member is turned in one direction and for taking a new bite when the member is turned in the opposite direction. 45

3. In a lock of the character described, a stationary element, a member revolvable relative thereto, and a spring-pressed plunger 50 projecting eccentrically from said member adapted to ride in a ratchet. 55

4. In a lock of the character described, a cylindrical body, a plurality of longitudinally movable tumblers therein, a bore in the cylindrical body for the reception of a guide element on a key, said movable tumblers being adapted to be pushed by prongs on the key, and spring means provided in the bore bearing on the guide element for yieldingly holding the same in place. 60

In testimony whereof I affix my signature.

FRANK J. HELMUTH.
